UNITED STATES PATENT OFFICE.

GLENN E. HOLMES, OF ST. LOUIS, MISSOURI, ASSIGNOR TO MEXICAN-AMERICAN HAT COMPANY, OF ST. LOUIS, MISSOURI, A CORPORATION OF MISSOURI.

HAT.

Application filed August 17, 1927. Serial No. 213,597.

This invention relates to hats and more particularly to that type of hat in which the crown is more or less flexible so that the size of the hat may be adjusted by adjusting the length of the hat band.

One of the objects of this invention is to provide novel means for retaining the hat band in place.

Another object is to provide such means which shall be effective in holding the hat band in place while at the same time allowing free movement thereof for adjustment and which shall be inconspicuous.

Further objects will appear from the following description, taken in connection with the accompanying drawing, which shows a hat embodying this invention.

This invention may be applied to any type of hat in which the hat band is adjustable for the purpose of varying the size of the hat or otherwise. As illustrated in the drawing, the same is applied to a summer straw hat having a crown 1 and a rim 2. Such hats are ordinarily made of light straw and both the rim and the crown are flexible. A hat band 3 surrounds the lower portion of the crown 1 and is provided with a buckle 4 or other device for securing the ends of the band 3 in various adjusted relations. As the crown is flexible, the band 3 may be drawn up so as to shorten the same, and the crown will thereby be contracted to a smaller size. By lengthening the band 3, as by adjustment thereof by the buckle 4, the crown is permitted to expand to a larger size. In this way the same hat may be adjusted to fit different sized heads. Accordingly, a dealer in such hats may carry a limited range of sizes, each size being capable of adjustment over a considerable range.

Since the band 3 fixes the size of the crown, said band usually fits the crown snugly in its adjusted position and, for the smaller sizes, may be drawn fairly tight.

As the crown 1 is tapered upwardly, there is a tendency for the band to work itself way up the taper so that it leaves its position at the lower part of the crown. When this happens, of course, the lower part of the crown, where it fits the head, is permitted to expand and will no longer have a proper fit. In order to avoid this, means are provided to retain the band 3 in place

around the lower portion of the crown next to the rim 2.

A line of stitching 5 may be run through the band 3 and the crown of the hat at the front so as to secure the band to the crown in order to prevent slipping. The remaining portion of the band is not secured to the crown so that it is permitted movement relatively to the crown for the purpose of adjustment. At the rear portion of the crown, however, the band is held in place by a strip 6, which is sewed to the crown by a line of stitching 7 or otherwise secured thereto. The strip 6 is secured to the crown above the band 3 and extends downwardly over the band so as to confine the upper edge thereof and hold the same against slipping upwardly. At the same time, the band is free to move longitudinally for adjustment of the size of the hat. The strip 6 is preferably constructed of stiff or semi-rigid material, such as celluloid, which will be flexible, so as to permit flexure of the crown and which at the same time is stiff enough to hold the band 3 in place. If the strip 6 is made of transparent celluloid, it will be nearly invisible at a short distance and will at least be so inconspicuous that it is not noticed under ordinary circumstances.

It will be seen, therefore, that this invention provides an effective construction for a hat of this type in which the band is secured against creeping upwardly on the crown, while at the same time it is free to move lengthwise for adjustment. The strip 6 extends downwardly over the upper edge only of the band 3 so as to leave the band free for lengthwise movement while retaining the same securely against creeping upwardly. The transparency of the strip 6 enables the band 3 to be seen through it so that from a short distance the strip is practically invisible.

It is obvious that various changes may be made, within the scope of the appended claims, in the details of construction without departing from the spirit of this invention; it is, therefore, to be understood that this invention is not limited to the specific details shown and described.

Having thus described the invention, what is claimed is:

1. A hat having an adjustable band surrounding the lower part of the crown there-

of, and a stiff transparent strip secured to the crown above the band and extending downwardly over the band to retain the same in place.

- 5 2. A hat having an adjustable band surrounding the lower part of the crown thereof, and a strip of transparent celluloid secured to the crown and extending over the band to retain the same in place.
- 10 3. A hat having an adjustable band surrounding the lower part of the crown thereof and fixedly secured thereto at one point, and a stiff strip secured to the crown and

extending over the band in relative slidable engagement therewith at another point to 15 retain the same in place.

4. A hat having an adjustable band surrounding the lower part of the crown thereof and fixedly secured thereto at one point and a transparent strip secured to the crown 20 and extending over the band at another point to retain the same in place, said band being slidable relative to said strip.

In testimony whereof I affix my signature this 14th day of July, 1927.

GLENN E. HOLMES.
